(57) **CLAIM**

The ornamental design for a bottle, as shown and described.

DESCRIPTION

FIG. 1 is a perspective view of a bottle showing our new design;

FIG. 2 is a front elevation view thereof;

FIG. 3 is a back elevation view thereof;

FIG. 4 is a right side elevation thereof;

FIG. 5 is left side elevation thereof;

FIG. 6 is a top plan thereof; and,

FIG. 7 is a bottom plan thereof.

The broken line showing of a bottle and crescent shapes on the bottle is included for the purpose of illustrating only and forms no part of the claimed design. The portion of broken lines shown around the handle of the bottle forms a boundary line of the claimed design.
